7 Claims. (Cl. 340—38)

This invention relates to electronic apparatus, and more particularly to electronic counting and control apparatus.

In the complex relationships of modern activities, it becomes increasingly important to provide automatic means for taking count of and controlling the movement of individual items. An example of a situation requiring such improved counting and control means is the flow of vehicular traffic on our streets and highways. A wide range of conditions are imposed upon systems designed for this purpose. First, the system must be reliable under various conditions of ambient lighting, from brilliant sunlight to dark of night; under various conditions of ambient temperature, from tropic heat of summer to the freezing cold of winter. It must be capable of producing a reliable signal under various conditions of road surface including blacktop, macadam, or concrete. The situation is further complicated in that the signals must continue to be reliable even though the ambient conditions change considerably. For example, one condition is presented to the system when the roadway is hot and dry, a considerably different ambient condition prevails during and following a rain or snowfall, leaving the roadway either wet or snow covered. Again, the situation is still further complicated by the variations in velocity and frequency of the passage of the vehicles as well as the variations in the spacing between vehicles.

It is an object of the present invention to provide an improved system for sensing and signaling the passage of objects past a sensing station.

It is another object of this invention to provide a sensing and signaling system as set forth which is especially adapted for use as a roadway vehicular traffic sensing and signaling system.

It is a further object of this invention to provide an improved traffic sensing and signaling system which is capable of meeting all of the requirements set forth above.

Previous traffic sensing and signaling devices have, for one reason or another, required considerable ancillary hardware for their installation such as pressure plates imbedded in the roadbed or special support poles and means, such as special mounting arms, to support the sensing means directly over the traffic lane to be sensed.

It is a still further object of this invention to provide an improved traffic sensing and signaling means which requires little or no ancillary hardware for its installation but may be mounted conveniently high on available utility poles at the side of the roadway and aimed at the lane or lanes to be sensed.

It is yet another object of this invention to provide a traffic sensing and signaling system which is relatively inexpensive in initial cost and in operation and which requires little or no maintenance or attention.

In accomplishing these and other objects, there has been provided, in accordance with the present invention, an object sensing and signaling system which features a source of infra-red radiation and means for focusing the beam therefrom onto the path to be followed by the object to be sensed. An infra-red sensing means is positioned to receive reflections of the emitted beam. Signals from the sensing means are applied as input signals to a transistor amplifier. From the transistor amplifier, the amplified signals are applied, first, to an output control circuit, and, second, to a feedback circuit. The feedback

2

circuit is characterized in that the signals developed therein are applied to control the intensity of the radiation from the infra-red source, thereby to maintain the ambient condition "seen" by the sensing device substantially constant. With this arrangement, the system becomes self compensating for any of the several anticipated conditions as well as for changes in the internal condition of the apparatus.

A better understanding of this invention may be had from the following detailed description when read in conjunction with the accompanying drawings, wherein:

FIG. 1 is a graphical representation of a traffic sensing and signaling system embodying the present invention and shown in situ;

FIG. 2 is a schematic circuit diagram of a system embodying the present invention; and

FIG. 3 is a graph representing certain signal relationships occurring in the circuit shown in FIG. 2.

Referring now to the drawings in more detail, there is shown in FIG. 1 a representation of a traffic sensing and signaling means 2 mounted on a utility pole 4 by the side of a roadway 6. From the apparatus 2 there is shown a broken line 8 representing a beam of infra-red radiation, emanating from the apparatus 2, impinging on the surface of the roadway, and, because of the inherent roughness of the road surface, being reflected, at least in part, back to the apparatus 2. As a vehicle passes along the roadway and into the beam 8, the character of the reflected beam will be changed, as will be more fully set forth hereinafter, by the surface of the vehicle. The apparatus 2 detects this change in reflection to produce a signal in accordance therewith. The signal thus produced may be used to actuate a counter which may, in turn, be used to merely accumulate statistical data or may be used to automatically program the actuation of associated traffic control signals.

Suitable apparatus for the sensing and signaling means 2 is shown in substantial detail in FIG. 2. An infra-red radiation sensing means such as a lead-sulphide cell 10 is positioned to receive radiation from the surface of the roadway 6 (FIG. 1) through suitable focusing optics represented by a lens 12. The cell 10 is connected at one end to a power supply bus 14 and, at the other end is connected to ground through the primary winding 16 of a coupling transformer 18. The transformer 18 has a secondary winding 20 to which is coupled the input stage 22 of a transistor amplifier. The transistor amplifier further includes, as successive stages of amplification transistors 24, 26, 28 and 30. Between the output of the transistor 26 and the input of the transistor 28 there is connected a series tuned coupling network including a capacitor 32 and an inductor 34. As will be shown hereinafter, the control signal applied to the input of the system is chopped at a predetermined frequency, say 400 cycles per second. The just mentioned tuned network is tuned substantially to that frequency to eliminate the effect of spurious signals on the subsequent elements of the system.

The output of the last stage 30 of the transistor amplifier is coupled to the primary winding 36 of a coupling transformer 38. The transformer 38 has a center-tapped secondary winding 40. Each of the extreme ends of the secondary winding 40 of the transformer 38 is connected to the base electrode of a transistor 42, 44 respectively. The center-tap of the secondary 40 is grounded. The emitter electrodes of the two transistors 42 and 44 are connected through a suitable filter to ground. The two collector electrodes are connected together to provide a D.C. output signal which is a function of the signal detected by the detector element 10. Thus, the

transformer 38 and the two transistors 42 and 44 constitute a full-wave rectifier circuit.

The rectified output from the rectifier is applied through a series of crystal diodes to a corresponding group of transistors. A first crystal diode 46 is connected between the output of the rectifier and the base electrode of the transistor 48. Similarly, this second diode 50 is connected between the output of the rectifier and the base electrode of the transistor 52. Again, diode 54 is connected between the output of the rectifier and the base electrode of the transistor 56. And further, diode 58 is connected between the output of the rectifier and the base electrode of the transistor 60. With the foregoing arrangement the output signal from the rectifier may be applied to each of the four transistors with the crystal diodes providing the necessary isolation to prevent interaction between the respective transistors. It will be noted that the transistors 48 and 52 are of one conductivity type while the transistors 56 and 60 are of the opposite conductivity. The purpose of this arrangement will appear more fully hereinafter.

The bias voltage for these four transistors as well as for subsequent transistors is obtained by a voltage divider comprising a series string of resistors connected between the negative voltage supply V^- and ground. These resistors 62, 64, 66, 68, 70 and 72, respectively, are arranged to give progressively different levels of bias signal as will be seen to be necessary. Thus the emitter of the transistor 48 is connected to the junction between the resistors 70 and 72. The emitter of the transistor 52 is connected to the junction between the resistor 68 and 70. Similarly, the emitter of the transistor 56 is connected to the junction between the resistors 64 and 66, while the emitter of transistor 60 is connected to the junction between resistors 62 and 64. The junction between resistors 66 and 68 is nominally at the same static level as the rectified output from the transistors 42 and 44.

The collector output of the transistor 48 is applied to the base input of a subsequent transistor 74. Similarly the collector output of the transistor 60 is directly coupled to the base input of a subsequent transistor 76. In a like manner, the collector output of the transistor 52 is directly coupled to the base input of the transistor 78 and the collector output of the transistor 56 is connected to the base input of the transistor 80. The collector of the transistor 74 is connected to the V^- supply line while the collector of transistor 76A is connected to ground. The junction between the resistors 66 and 68, forming the bias voltage-divider center point, is connected through a first crystal diode 82 to one end of the coil 84 of the relay 86. The emitter of transistor 74 is also connected to the same end of the relay coil 84. The same junction between the resistors 66 and 68, is also connected through a similar crystal diode 88 to the opposite end of the relay coil 84 and to the emitter of the transistor 76. It is to be noted the diodes 82 and 88 are of opposite polarity. A capacitor 90 is connected between the collector and the emitter of the transistor 74. Similarly a capacitor 92 is connected between the emitter and the collector of the transistor 76. The junction between the resistors 66 and 68 is also connected to the emitters of both transistors 78 and 80, the two emitters being connected together. The collector of the transistor 78 is connected through the energizing coil of a relay 94 to the V^- power supply line. A capacitor 96 is connected between the collector and the base of the transistor 78. In a like manner, the collector of the transistor 80 is connected through the energizing coil of a relay 98 to ground. The capacitor 100 interconnects the base and the collector of the transistor 80. Relay 86 when energized controls the actuation of a movable blade 102 between a pair of fixed contacts 104. These three contacts are arranged for connection to a suitable utilization apparatus as an output means.

The relay 94 also includes a movable blade operating

between a pair of fixed contacts, as does the relay 98. The movable contact of the relay 94 is directly connected to the movable contact of the relay 98. The upper or normally closed contact of the relay 94 is directly connected to the upper and normally closed contact of the relay 98. Both of these contacts are connected to one terminal of an alternating current source. The lower and normally open contact of the relay 94 is connected through the field winding 108 of a low speed synchronous motor 110 to the other terminal of the alternating currents source. Similarly the lower and normally open contact of the relay 98 is connected through the field winding 112 of a substantially identical motor 114 to the opposite terminal of the alternating current source. The motors 110 and 114 are arranged for rotation in opposite directions with respect to each other when one or the other is energized by the closing of the relay 94 or the relay 98, respectively.

The motors 110 and 114 are arranged to control the position of a slider 116 along a slidewire 118. The slidewire 118 is connected in a voltage divider across the output of the power supply source. The supply source includes means for connection to an A.C. source 120 which is connected to the primary winding of a transformer 122. The secondary winding of the transformer 122 is connected in a conventional full-wave rectifier arrangement with a pair of diodes 124 and suitable filtering. The voltage divider network including the slidewire 118 is connected across the output terminal of this full wave rectifier. The slider 116 of this slidewire 118 is connected to the base electrode of a transistor 126. The transistor 126 comprises a control element for controlling the amount of current fed from the power supply through an infra-red emitter represented as the lamp bulb 128. The infra-red radiation emitted by the bulb 128 is passed through suitable optics represented by the lens 130 and focused on the roadway 6 (FIG. 1). Interposed in the beam of radiation emitted by the bulb 128 is a suitable light chopper represented by the shutter element 132. This shutter element is represented as a rotary member which is in turn driven at a constant speed by a suitable motor 134 which is shown connected directly across the A.C. input leads.

Inasmuch as it is anticipated that the present apparatus will be used under extremes of climatic conditions including those of extremely low and icy conditions there has been provided a pair of heater elements 136 and 138 respectively connected across the A.C. supply leads and energized through actuation of a thermostatic switch 140. These heater elements are arranged to prevent the formation of ice and snow on the optical system.

In operation it is assumed that the infra-red bulb 128 is emitting a predetermined amount of radiation chopped by the chopper 132 and focused by the lens 130 on the roadway 6. A portion of the chopped infra-red emission impinging on the roadway is reflected back through the lens 12 onto the sensing element 10. The element 10 is characterized in that the resistance thereof to current flow is changed in accordance with the amount of radiation impinging thereon. It will be remembered that the radiation emitted by the bulb 128 is chopped at a desired frequency such as 400 cycles per second. Thus for a constant energization of the bulb 128 there will be produced at the receiving element 10 a signal of constant amplitude and varying at 400 cycles per second. This 400 cycles per second signal is coupled through the transformer 18 to the input stage 22 of the transistor amplifier. The effect of all random radiation other than the 400 cycle per second signal is eliminated through the tuned circuit including the capacitor 32 and the inductor 34. Thus the signal fed to the primary 36 of the transformer 38 is representative of the background signal as received from the roadway 6. This signal is illustrated in FIG. 3 as that portion of the signal represented as "background." It will be noted that this

signal falls between the dotted lines "b" and "c" in so far as the amplitude indication is concerned. Considering only this portion of the signal as it effects the remainder of the apparatus, it may be seen that this signal is fed to the rectifier including the transistors 42 and 44. Let it be assumed that the V— supply has a value of -20 volts. The static output condition of the rectifier is chosen to be at -10 volts. The bias values established for the transistors 52 and 56 by the voltage divider resistors 62 through 72 are such that these two transistors are biased into heavy or saturated conduction. With this conductivity condition of the transistors 52 and 56, the transistors 78 and 80 are biased to cut-off and both relays 94 and 98 remain unenergized. Assume now that the amplitude of the signal fed to the primary 36 of the transformer 38, for some reason or another, increases slightly over a long term period. This increase in signal will be expressed as an increase in the signal level put out by the rectifier and applied as input to the transistor 52. The increasing signal applied to the base of the transistor 52 reduces its conductivity, thereby changing the bias on the transistor 78, allowing it to become conductive, the emitter of the transistor 78, being referenced to the center point of the voltage divider represented by the resistors 62 through 72. As the transistor 78 becomes conductive, current flowing therethrough flows also through the energizing coil of the relay 94. This causes the relay 94 to be picked up, thereby energizing the winding 108 of the motor 110. Energizing the motor 110 causes the slider 116 to move along the slide-wire 118, and change the bias on the transistor 126. This change in bias on the transistor 126 reduces the current flowing therethrough and accordingly reduces the current flowing through the infra-red radiation source 128. This reduction in the amount of radiation from the source 128 will be of an amount necessary to offset whatever caused the increase in signal applied to the input of the transformer 38. When the output of the rectifier has again reached a nominal value substantially equal to the center point of the voltage divider, i.e., approximately -10 volts in our illustrative, example, transistor 52 will resume its heavy conduction, again biasing the transistor 78 to cutoff.

Similarly if the signal applied to the input of the transformer 38 had decreased the transistor 56 would have been operated at a reduced conductivity condition and would thereby have biased transistor 80 into a state of conduction, thereby causing the relay 98 to be picked up. This would, in turn, have energized the winding 112 of the motor 114 causing the slider 116 to move in the opposite direction along the slide-wire 118, thereby causing the conductivity of the transistor 126 to increase and, in turn, increasing radiation emitted by the member 128. It may be seen through the foregoing operation, the apparatus herein described is automatically self-compensating for any ambient condition which may be presented thereto. The system is self-centering on the bias point established by the mid-point of the voltage-divider resistors string. In order that the system be relatively insensitive to changes of short duration which may cause an erroneous indication in the ultimate output the changes in the condition of the slider 116 along the slide-wire 118 are made to be extremely slow. For example the motors 110 and 114 respectively can be synchronous motored designed to have an output of rotation of approximately 4 revolutions per hour, thus, providing an integrated output of the ambient condition of the system which has an effective integration time constant of relatively long duration.

Now let it be assumed that the system has stabilized itself, as aforesaid, and that a motor vehicle passes along the roadway interrupting the reflection pattern of the infra-red beam. Because of the complexity of the contours of the shiny surfaces of modern automobiles, the reflection to the sensing element 10 may be either in-

creased appreciably or decreased appreciably, depending on whether the portion of the contour of the vehicle presents a surface which is approximately perpendicular to the infra-red beam or one which is at a substantially smaller angle with respect to the infra-red beam. In fact a single vehicle may present a series of rapidly changing increases and decreases in the reflected signal. These signals as received by the sensing element 10, amplified by the transistor amplifier, and applied to the input transformer 38 are represented in FIG. 3 as the portion of the curve designated "object detection." These signals also are applied to the full-wave rectifier where they are rectified and presented to the following circuitry much in the manner of the signal previously described. Since these signals are of substantially higher frequency characteristic than the one previously described the capacitors 96 and 100 prevent them from appreciably influencing the operation of the motors 110 and 114. However, they are applied to the input of the transistors 48 and 60. Much in the manner of the operating characteristic of the transistors 52 and 56, transistor 48 and 60 are also biased into heavy conduction. There is one significant difference between the operation of transistors 48 and 60 as distinguished from that transistors 52 and 56. That is that the bias to be overcome by the input signal is considerably higher in the case of the transistors 48 and 60 than in the case of the other two. This bias level is represented by the dashed lines "d" and "e" in FIG. 3. Thus if the signal increases beyond dashed line "d" of FIG. 3 the conductivity of the transistor 48 will be reduced thereby biasing transistor 74 into conduction. When the transistor 74 conducts, its current path may be found to flow from the center point of the voltage divider resistor string, that is, the junction between resistors 66 and 68 through the diode 88, the exciting winding 84 of the relay 86, thence to the emitter and collector of the transistor 74. Thus, when the transistor 74 is rendered conductive, the relay 86 is energized, causing the blade 102 to be transferred from the normally closed position to contact with the other one of the two fixed contacts 104. On the other hand, when the beam is reflected away from the sensing element 10 and the signal applied to the transformer 38 drops below the level indicated by the dash line "e" of FIG. 3, then the transistor 60 has its conductivity reduced, biasing the transistor 76 into conductivity. The transistor 76 being of the opposite conductivity type from that of transistor 74, we find that its conduction path flows from the collector to the emitter thereof, thence through the energizing winding 84 of the relay 86, through the crystal diode 82, thence to the junction between the resistors 66 and 68. This current flow also causes the relay 86 to be picked up, or, in this case, to remain picked up. The capacitors 90 and 92 connected between the emitter and collector respectively of these two transistors provide a small integrating action to prevent an inadvertent dropout of the relay 86 during the transition of the transfer of conductivity from one of these transistors to the other. When the signal applied to the transformer 38 has again returned, for a significant period, to the amplitude represented as "background" in FIG. 3, then relay 86 will be allowed to drop out. Thus the complex reflection pattern from a single vehicle causes only a single actuation of the relay 86. This in turn produces a single count in the utilization apparatus 106. As hereinbefore mentioned the utilization apparatus 106 may comprise merely a counter for compiling statistical data or the output utilization apparatus may include means for programming the operation of controlled traffic signals.

From the foregoing it may be seen that there has been provided in accordance with the present invention an improved sensing and signaling means, for use in such situations as counting vehicular traffic along a roadway, which is characterized in that it is capable of adjustment to compensate for anticipated situations involving

conditions of ambient temperature, ambient light or conditions of reflectivity of the roadway surface. It is further characterized in that it is capable of producing an accurate count of the passage of vehicle traffic past a given point and requires a minimum care and attention from an operator.

What is claimed is:

1. An electronic sensing and signaling apparatus comprising means for producing a beam of signal radiation, means for directing said beam of radiation toward a path along which an object to be sensed passes, signal producing means for detecting reflections of said radiations from said path and from said object to be sensed, signal selecting means for distinguishing between signals produced as a result of reflections from said path and signals produced as a result of reflections from said object to be sensed, means responsive to said signals produced as a result of reflections from said path to change the intensity of the radiation from said beam producing means in accordance with changes in intensity of said reflections from said path, and means responsive to said signals produced as a result of reflections from said object to produce an output signal.

2. An electronic sensing and signaling apparatus comprising means for producing a beam of infra-red signal radiation, means for directing said beam of radiation toward a path along which an object to be sensed passes, infra-red radiation sensitive signal producing means for detecting reflections of said infra-red radiations from said path and from said object to be sensed; signal selecting means for distinguishing between signals produced as a result of reflections from said path and signals produced as a result of reflection from said object to be sensed, means responsive to said signals produced as a result of reflections from said path to change the intensity of the radiation from said beam producing means in accordance with changes in intensity of reflections from said path, and means responsive to said signals produced as a result of reflections from said object to produce an output signal.

3. An electronic sensing and signaling apparatus comprising a source of infra-red radiation, means for producing a beam of the radiations from said source, means for directing said beam of radiation toward a roadway along which vehicles to be detected pass, infra-red radiation sensitive signal producing means for detecting reflections of said infra-red radiations from said roadway and from passing motor vehicles, means for amplifying signals produced by said signal producing means, signal

selecting means connected to said amplifying means for distinguishing between signals produced as a result of reflections from said roadway and signals produced as a result of reflections from said passing vehicles, means responsive to said signals produced as a result of reflections from said roadway to change the intensity of radiation from said source in accordance with changes in intensity of the reflections received from said roadway, and means responsive to said signals produced as a result of reflections from said passing vehicles to produce an output signal.

4. The invention as set forth in claim 3 wherein said means responsive to signals produced as a result of reflections from said roadway includes a transistor current control means, a pair of electromagnetic relays, said relays being operable in accordance with the current control action of said transistor current control means, reversible motor means responsive to the actuation of said relays, and means responsive to the operation of said motor means to control the amount of energizing current applied to said source of infra-red radiation.

5. The invention as set forth in claim 4 wherein said last mentioned means comprises a slidewire potentiometer having a slider movable by said operation of said motor means, said slider being connected to control the operating bias on a transistor serially connected in circuit with said infra-red source.

6. The invention as set forth in claim 5 wherein said means responsive to said signals produced as at result of reflection from said passing vehicles includes a further transistor current control means, a relay, said relay being operable in accordance with the current control action of said further transistor current control means, said actuation of said relay comprising an output signal for said apparatus.

7. The invention as set forth in claim 3 wherein said beam producing means includes means for chopping said beam at a predetermined frequency and said amplifying means includes means tuned to said frequency to effect a rejection of spurious signals.
